UNITED STATES PATENT OFFICE.

WILLIE O. BESAW, OF REEDLEY, CALIFORNIA.

FUSE PLUG.

Application filed February 6, 1923. Serial No. 617,277.

To all whom it may concern:

Be it known that I, WILLIE O. BESAW, a citizen of the United States, residing at Reedley, in the county of Fresno and State 5 of California, have invented certain new and useful Improvements in Fuse Plugs, of which the following is a specification.

The primary object of this invention resides in the provision of a fuse plug, where- 10 in the same is provided with two of the usual fusible members for substantially doubling the life of the plug.

A further object of the invention is the provision of such an article that is com- 15 paratively simple of construction, and inexpensive of manufacture, the plug embodying relatively few parts and these so correlated as to produce a compact and highly useful article.

20 The nature and advantages of the invention will be better understood when the following detailed description is read in connection with the accompanying drawings, the invention residing in the construction, 25 combination, and arrangement of parts as claimed.

In the drawings forming part of this application, like numerals of reference indicate similar parts in the several views, 30 and wherein:

Figure 1 is an elevational view of a plug constructed in accordance with the present invention.

Figure 2 is a top plan view thereof.

35 Figure 3 is a transverse cross sectional view upon the line 3—3 of Figure 1.

Figure 4 is a vertical transverse sectional view upon the line 4—4 of Figure 1.

40 Figure 5 is a perspective view of the major member of my plug, and

Figure 6 is a side elevational view of one of the thread sleeves employed by me.

With particular reference to the drawings, my fuse plug embodies the provision 45 of a cylindrical-shaped solid wooden plug 5 bevelled at its opposite ends as at 6. I have stated that this plug 5 is of wood but it is nevertheless understood that other suitable material may be used without departing 50 from the spirit of the invention.

The upper and lower ends of the member 6 are each provided with a cross bore 7, these bores being at opposite sides of the plug 5 and in parallelism with each other.

55 By a consideration of Figure 4, it will at

once be apparent that one end of each of the bores 7 terminates at a point centrally of the ends of the plug, and that the opposite ends of each of these bores 7 terminate at a point beneath the central longitudinal axis of the plug, or in other words, each of these bores extend at an angle substantially forty-five degrees with respect to the central vertical axis of the plug.

Within each of the bores 7, there is positioned a fusible wire 8, the opposite ends of each being coiled as at 9 for receiving tacks or the like fastening means 10, whereby these fusible wires 8 are maintained within their respective bores.

Upon the plug 5 adjacent the opposite ends thereof are sleeve members 12, each of which is formed with a thread 13, which thread is in the form of a corrugation as more clearly shown in Figures 3 and 4. 75 These sleeves 12 are maintained in position upon the plug 5 by soldering the upper edge of the same to the heads of the side tacks 10 as at 14, which soldering also connects the fusible wires 8 with the upper and lower 80 sleeves 12.

In view of the above description, it will at once be apparent that the end tacks 10 form one of the contacts and that the sleeves 12 form the other contacts, and in the practical application of the above described fuse plug, should one of the fusible wires 8 burn out or become otherwise disrupted, the plug may be removed from its socket and inverted, to be again received within the 90 socket.

While I have herein shown and described the preferred embodiments of the present invention, it is nevertheless to be understood that minor changes may be made therein, 95 without departing from the spirit and scope of the invention as claimed.

What I claim as new is:

A fuse plug comprising a body of wood having a bore leading in from one end thereof and extending through the side of the body, a fusible element threaded through the bore, a tack extending into the end of the body and contacting with the fusible element, a sleeve circumscribing the body, 100 and a second tack fixed to the sleeve and extending into the side of the body and contacting with the fusible element.

In testimony whereof I affix my signature.

WILLIE O. BESAW.
